Primary Examiner — Keli L Hill*Assistant Examiner* — Sara S Sahneh(74) *Attorney, Agent, or Firm* — J. Bennett Mullinax LLC(57) **CLAIM**

The ornamental design for an air ratchet, as shown and described.

DESCRIPTION

FIG. 1 is a left side perspective view of the air ratchet as shown in FIG. 1;

FIG. 2 is a right side view of the air ratchet as shown in FIG. 1;

FIG. 3 is a front view of the air ratchet as shown in FIG. 1; FIG. 4 is a rear view of the air ratchet as shown in FIG. 1; FIG. 5 is a bottom view of the air ratchet as shown in FIG. 1;

FIG. 6 is a bottom view of the air ratchet, as shown in FIG. 1; and,

FIG. 7 is a top perspective view of the air ratchet as shown in FIG. 1.

The broken lines in FIGS. 4-7 are for the purpose of illustrating portions of the air ratchet and form no part of the claimed design.

1 Claim, 6 Drawing Sheets(56)
